UNITED STATES PATENT OFFICE.

FREDERICK J. BOSSE, OF STRATFORD, CONNECTICUT.

ARRANGEMENT FOR TYING PACKAGES.

Application filed December 9, 1924. Serial No. 754,811.

My invention relates broadly to receptacles and more particularly to closures for boxes provided with cord fasteners for facilitating the tying and untying of boxes and article carriers.

One of the objects of my invention is to provide a box closure with means for eliminating the tying of knots in the securing cord used in wrapping packages whereby the cord may be rapidly secured on the package or quickly removed therefrom for opening the package.

Another object of the invention is to provide means integral with the walls of the receptacle for enabling the securing cord to be fastened around the receptacle without looping the cord at the points of crossing whereby the cord may be fastened under the integral means without the tying of knots ready for the immediate opening of the receptacle by unwrapping the cord from the integral means.

A further object of the invention is to provide a flat sheet member with tongues integral therewith capable of being slightly turned up to enable the securing cord to be wedged beneath the tongues for quickly fastening or unfastening the cord around the receptacle.

Another object of the invention is to provide a flat removable member which may be placed adjacent one wall of the receptacle, the member being provided with a sheet like portion which directly contacts with a wall of the receptacle and another sheet like portion having tongues therein which may be lifted up to enable the cord encircling the receptacle to be quickly wedged between the lower surface of the tongues and the sheet which contacts with the receptacle.

A still further object of the invention is to provide auxiliary resilient means which may be applied to the tongues of the fastener serving as a reinforcement and as means for maintaining the tongues in depressed relationship clamping the cord around the receptacle.

My invention will be more clearly understood from the following specification and by reference to the accompanying drawings, in which:

Figure 1 is a perspective view of a box showing the cord fastener closure of my invention integral with the box cover and the method of securing the fastening cord around the receptacle without the tying of

knots; Fig. 2 is a perspective view of a separate member which may be placed adjacent a wall of a box to enable the fastening cord to be secured without the tying of knots; 60 Fig. 3 is a perspective view of a modified form of separate cord fastening device; Fig. 4 is a cross sectional view taken on line 4—4 of the cord fastening device shown in Fig. 3; Fig. 5 is a plan view of a cord fastening device having resilient members arranged adjacent the cord fastening tongues for reinforcing the tongues and constantly depressing them in position for clamping the securing cord; and Fig. 6 is a cross sectional 70 view of the cord fastening means taken on line 6—6 of Fig. 5.

Heretofore in the art whenever cord or twine has been used in making packages safe for handling it has been necessary to 75 provide substantial knots to unite the two ends of the cord or other fastening means have been provided which are relatively expensive in manufacture and ineffective under practical conditions met with in continued use. The tying of knots in a fastening cord is at times very inconvenient particularly for the subsequent reopening and retying of the package. Furthermore a knot always weakens the cord at the point 80 of tying which of course is equivalent to diminishing the security of the closure. In the usual way of fastening a package loops are formed where the cord crosses itself and these points of crossing are exposed to chafing while being handled which tends to cut and destroy the fibers of the fastening cord. By my present invention I avoid previous disadvantages by providing a plurality of 85 tongues which may be perforated from one wall of the receptacle which it is desired to fasten by the present method. Four tongues may be provided and the cord passed under one of the tongues, then under an adjacent tongue and around the package, again under the first tongue, next under another adjacent tongue and around the package under a tongue opposite to that under which the cord was started and finishing under one 90 of the adjacent tongues. The device may or may not be integral with the package. It may be constructed of pressboard, leather, metal or plastic material although I prefer cardboard and such soft material as that 95 has a minimum tendency to chafe the cord. Where the device is separate from the receptacle the tongues may be perforated from a

110

flat sheet of material which is placed adjacent one wall of the box to be fastened. In order to prevent the tongues being depressed in an opposite direction to that desired for insertion of the cord I may provide another flat sheet on the rear of the sheet containing the tongues which flat sheet is placed directly in contact with one wall of the box to be fastened. In order to 10 reinforce the tongues and maintain the tongues depressed to facilitate clamping of the cord I may provide resilient members which bear against the tongues. By my arrangement the contents of packages may be 15 examined by quickly unwrapping the cord from the fastening means and the package resealed by again quickly wrapping the cord about the fastening means. This quick unwrapping and rewrapping of packages 20 has application for example in parcel post shipments where postal regulations give authority for the examination of the contents of packages. My arrangement allows the use of less twine and lighter twine, as there are 25 no loops formed by crossing twine as there are in knotting. This arrangement results in a saving of twine, for the same twine may be used over and over again. The same twine will make for better security, because 30 there is no chafing of it throughout its length. For this reason I prefer cardboard or other soft materials, rather than metal, etc., such as would have a tendency to cut or chafe the twine.

35 Referring now more particularly to the drawings reference character 1 represents a paper receptacle having a closure 2 as its cover. Stamped out of the cover 2 or perforated therein are tongues 3, 4, 5, and 6 which are integral with the cover 2. The 40 ends of the little tongues are slightly turned up so as to facilitate the entering of the twine. The tying cord is indicated as starting at 7 and entering under tongue 3 as shown at 8 then passing over tongue 4 at 9, under tongue 5 and 10 and around the package at 11. The cord returns at 12 and again passes under tongue 3 at 14, then under tongue 4 at 15 and around the package 45 at 16. The cord returns around the package at 17 and passes under tongue 6 as shown at 18 and finishes under tongue 4 at 19. The wrapping of the package is very rapid and the unwrapping is equally as rapid, the 50 cord being clamped between the under surfaces of the tongues and the side of the cover adjacent the tongues. In Fig. 2, I show how the tongues 3, 4, 5, and 6 may be perforated from the pressboard or hard, tough sheet 55 20 which is laid on the package and the twine passed around it as previously described. In Fig. 3, I have shown a flat sheet 21 fastened to that side of member 20 which is opposite the side where the twine is laid, such an arrangement preventing the 60 65 70 75 80 85 90 95 100 105 110 115 120 125 130

tongues from being depressed in handling which might cause delays in making the twine enter. The sheets 20 and 21 are secured together by inexpensive means such as eyelets 22, 23, 24, 25, and 26. The cord 70 enters between the under surface of the tongues 3, 4, 5, and 6 and the upper surface of sheet 21 immediately below the tongues. To reinforce the tongues 3, 4, 5, and 6 a piece of sheet metal 27 may be fastened to the top of the tongued cardboard, as shown in Fig. 5 to serve as a reinforcement in the center and by spring action to keep the tongues depressed, which is necessary in case of the cardboard becoming wet, or when used with very heavy cord. This sheet metal 27 is preferably in the shape of a four pointed star with resilient arms urging each of the tongues 3, 4, 5, and 6 in the direction of sheet 21. The four armed resilient member 27 may be secured with relation to the sheets 20 and 21 by means of eyelet 26.

While I have described my invention in certain preferred embodiments it is to be understood that my invention is not limited to these particular constructions alone and that modifications may be made within the scope of the appended claims without departing from the spirit of my invention.

What I claim and desire to secure by Letters Patent of the United States is as follows:

1. In a cord fastener and closure for receptacles, a receptacle closure, a flat sheet like member adjacent said closure, a second sheet like member adjacent said first mentioned sheet like member on the side opposite to said closure and tongues carried by said second sheet like member, said tongues being upturned at their ends to enable a securing cord to be clamped between said tongues and said member whereby said cord may be passed around said receptacle and fastened beneath said tongues for securing said closure on said receptacle.
2. In a cord fastener and closure for receptacles, a receptacle closure, a flat sheet like member adjacent said closure, a second sheet like member clamped adjacent said first mentioned sheet like member on the side opposite to said closure and tongues carried by said second sheet like member, said tongues being upturned at their ends to enable a securing cord to be clamped between the under surface of said tongues and the upper surface of said first mentioned sheet like member immediately below said tongues whereby said cord may be passed around said receptacle and fastened beneath said tongues for securing said closure on said receptacle.
3. In a cord fastener and closure for receptacles, a receptacle closure, a flat sheet like member adjacent said closure, a second

- sheet like member secured adjacent said first mentioned sheet like member on the side opposite to said closure, a plurality of tongues perforated from said second sheet like member and integral therewith, the ends of said tongues being slightly upturned whereby a securing cord may be clamped between the lower surface of said tongues and said first mentioned sheet like member and the upper surface of said first mentioned sheet like member and the cord passed around said receptacle and fastened under said tongues for securing said closure on said receptacle.
13. 4. In a cord fastener and closure for receptacles, a receptacle closure, a flat sheet like member adjacent said closure, a second sheet like member secured adjacent said first

mentioned sheet like member on the side opposite to said closure, a plurality of tongues 20 perforated from said second sheet like member and integral therewith, the ends of said tongues being slightly upturned whereby a securing cord may be clamped between the lower surface of said tongues and said first mentioned sheet like member, resilient 25 means for constantly urging said tongues against said first mentioned sheet like member with the top surfaces of said tongues flush with the plane of said second mentioned sheet like member whereby said securing cord may be passed around said receptacle and fastened under said tongues for securing said closure on said receptacle.

FREDERICK J. BOSSE.
